HENRY KIELBERG, OF MARTINS FERRY, OHIO, ASSIGNOR TO WHEELING STEEL CORPORATION, OF WHEELING, WEST VIRGINIA, A CORPORATION OF DELAWARE.

METHOD OF PRODUCING TAPERED EXPANDED-METAL RECEPTACLES.

Application filed April 10, 1926. Serial No. 101,201.

This invention relates to a method of forming reticulated metal receptacles of tapered form, and it has for its object to provide a simple and practical method of producing tapered bodies for waste baskets, waste paper burners and like receptacles.

In describing the invention in detail, reference is herein had to the accompanying drawings, in which—

10 Figure 1 is a side elevation of a plain hollow cylinder formed by uniting the ends of a rectangular sheet of expanded sheet metal;

15 Figure 2 is a side elevation of a tapered basket body formed from said cylinder; and

Figure 3 is a detail section of the metal fabric taken on line 3—3, Fig. 1.

Heretofore, in the formation of tapered receptacles from expanded metal sheets, it 20 has been the practice to preliminary stretch the rectangular sheet in such manner that it is elongated at one lateral edge to a sufficiently greater extent than at its opposite edge, and then to unite the ends of the sheet.

25 While such method is effective for producing the required tapered form of body, it is objectionable for certain reasons, among which may be mentioned that in the sheet-stretching operation, some of the meshes are 30 liable to become distorted to a greater or lesser extent than others.

In carrying out the method of the present invention, a rectangular sheet of expanded reticulated metal is first bent into cylindrical form, as shown in Fig. 1, and the meeting ends thereof are permanently joined, as by spot welding. The diameter of the cylinder 35 is substantially that desired at the bottom end of the basket body. The cylinder is then seated on end within the embrace of a shallow die 2, following which a tapered mandrel 3 of the size and form re-

quired is lowered vertically within the cylinder 1 to a seated, or substantially seated, position upon the bottom of said die. As 45 said mandrel descends within the cylinder, the latter is gradually expanded to the shape and size of the mandrel, as shown in Fig. 2, effecting substantially uniform spreading or opening of the meshes throughout the circumference of the basket body 4.

What is claimed is—

1. The method of producing tapered basket bodies, which consists in joining the ends of a rectangular expanded-metal sheet to form a cylinder, disposing said cylinder on end, and then lowering within said cylinder a tapered mandrel to effect gradual stretching of the sheet to conform to the size and shape of said mandrel.

2. The method of producing tapered basket bodies, which consists in joining the ends of a rectangular expanded-metal sheet to form a cylinder, disposing said cylinder on end within the embrace of a die, and then lowering a tapered mandrel within said cylinder to a seated position with respect to said die, such mandrel having the form and size required for the interior of the basket body.

3. The method of forming tapered basket bodies, which consists in producing an expanded metal sheet of rectangular form in which all parts thereof are expanded uniformly, then joining the ends of the sheet to form a cylinder, and finally introducing within the cylinder a tapered mandrel to subject the metal to additional stretching which progressively decreases in extent toward the end opposite that at which the mandrel enters.

In testimony whereof, I affix my signature.

HENRY KIELBERG.
